UNITED STATES PATENT OFFICE.

RENA D. QUACKENBUSH, OF MASON CITY, IOWA.

TOILET OR WATER-CLOSET SEAT COVER.

1,088,090.

Specification of Letters Patent.

Patented Feb. 24, 1914.

Application filed November 14, 1913. Serial No. 800,983.

To all whom it may concern:

Be it known that I, RENA D. QUACKENBUSH, a citizen of the United States, residing at Mason City, Cerro Gordo county, State of Iowa, have invented a certain new and useful Toilet or Water-Closet Seat Cover, of which the following is a specification, reference being had to the accompanying drawing, forming a part hereof, in which—

Figure 1 is a plan view of a water-closet seat with my new cover attached in operative position thereupon; Fig. 2 is a sectional view on line 2—2, Fig. 1; and Fig. 3 is a plan view of my new cover in fully open inoperative position detached from the seat.

This invention relates to a certain new and useful toilet or water-closet-seat cover, the object of my invention being to provide a simple, inexpensive, and portable cover especially adapted and designed for use for sanitary purposes upon, and in connection with, seats of the kind stated, which may be readily and quickly attached operatively upon, and detached from, the seat, which, when operatively attached upon the closet-seat, affords a smooth, even, comfortable, and sanitary seat for the body, which, when detached from the seat, may be compactly folded and conveniently carried, and which, in the preferred form of my cover, may be easily washed and, if necessary, disinfected, and thereby kept in cleanly, antiseptic condition.

With the above object in view, my invention resides in the novel form of my new seat-cover and in the novel construction and arrangement of the parts thereof, all as will hereinafter be described and afterward pointed out in the claim.

Referring now to the accompanying drawing, in which like reference letters refer to like parts throughout the several views, A indicates a water-closet of any approved form, and B its usual hinged, centrally open, and somewhat elliptical seat.

C indicates my new sanitary seat-cover, which is preferably made of a single piece of suitable flexible material, such as paper or preferably, as shown, water-proof and durable fabric having smooth and easily washed or cleaned surfaces, so that it may at all times be readily kept free from germs and in a highly cleanly and antiseptic condition. This cover C is also preferably

somewhat elliptical in plan view, as seen particularly in Fig. 3, to conform to or correspond with the usual seat B, and at its center the material thereof is cut-away preferably somewhat in the shape or form of a four-leaf clover (see Fig. 3) to provide a plurality of flexible centrally-disposed normally (as when cover C is in flat, unfolded, and detached position, as in Fig. 3) convergent seat-attaching tabs or extensions D integral with the main or body-portion c of cover C. At their free ends, each of the tabs D has fixed thereto one member E of a preferably glove or snap-fastening couplet, the other or complementing member F of each respective couplet being fixed to the main or body-portion c of cover C in coöperative position along the outer or marginal edge thereof.

When it is desired to use my new cover C upon a seat B, cover C may be first spread or placed thereupon with its main or body-portion c covering the upper surface of the seat; tabs D and the outer or marginal portion of body-portion c may then be overlapped on the under side or surface of seat B to bring fastening members E and F into engaging position, whereupon, as will be evident, on members E and F being snapped into coöperative engagement, my new cover C will be firmly held in attached operative position upon seat B, the central cut-away portion of cover C conforming, as seen in Fig. 1, to the central hole or opening of seat B and cover C, when in such position, completely covering seat B, preventing any portion of seat B coming into contact with the body, and affording for the body a smooth, comfortable, sanitary seat. On disengaging fastening members E and F, which may be easily done, cover C may be quickly detached from seat B, washed, if desired, folded into a compact package, and conveniently carried for further use. As shown in Fig. 3, cover C is preferably bound by tape or the like at both its outer edge and at the edge of its central opening, as at c' and c'', respectively.

It is to be understood that cover C may be of any particular or special shape or configuration as desired and may be provided with a greater or less number of attaching tabs D, and that other minor changes in the form, construction, and arrangement of the parts thereof may be made and substituted

for those herein shown and described without departing from the nature and principle of my invention.

Having thus described my invention, 5 what I claim and desire to secure by Letters Patent is:

As a new article of manufacture, a portable toilet-seat cover formed of flexible material and comprising a centrally cut-away body-portion integrally provided with a plurality of centrally-disposed normally convergent seat-attaching tabs, and complementing fastening members on said body-portion and said tabs, the fastening members 10 on said tabs being adapted to be engaged with the fastening members on said body- 15

portion to detachably hold the cover operatively upon a toilet-seat and the central opening in said body-portion conforming approximately to the hole in the toilet-seat 20 on the engagement of said tabs with said body-portion through their said complementing fastening members; substantially as described.

In testimony whereof, I have signed my 25 name to this specification, in the presence of two subscribing witnesses.

RENA D. QUACKENBUSH.
